UNITED STATES PATENT OFFICE.

JAMES A. CHADDERTON, OF SCOTTDALE, PENNSYLVANIA.

PHOTOGRAPHIC-PRINTING MACHINE.

1,232,219.

Specification of Letters Patent.

Patented July 3, 1917.

Application filed June 3, 1916. Serial No. 101,567.

To all whom it may concern:

Be it known that I, JAMES A. CHADDERTON, a citizen of the United States, residing at Scottdale, in the county of Westmoreland 5 and State of Pennsylvania, have invented certain new and useful Improvements in Photographic-Printing Machines, of which the following is a specification.

The present invention relates to photography and more particularly to new and useful improvements in photographic printing machines.

An object of my invention is to provide a photographic printing machine having 15 means for receiving the negative and sensitized paper, means for retaining the same in proper correlation for a printing operation, and automatic means associated therewith for supplying suitable light for the 20 printing process.

Another object of my invention is to provide in a printing machine of the class described a combination for holding the film and a piece of sensitized paper in proper correlation and means for supplying suitable printing light for a printing operation, the last said means being also arranged to supply a suitable modified light such as a red light, to enable the operator to properly 30 place the sensitized paper and film in the machine.

A further object of my invention is to provide a film printing machine of the class described which may be operated by hand 35 or foot as desired.

Other objects and advantages to be derived from the use of my improved printing machine will appear from the following detail description and the claims, taken with 40 an inspection of the accompanying drawing, in which:

Figure 1 is a perspective view of a photographic printing machine embodying the improvements of my invention,

Fig. 2 is a vertical sectional view taken through the same, showing the machine during a printing operation,

Fig. 3 is a disassembled perspective view of the film retaining member.

Fig. 4 is a perspective view of the preferred form of frame for receiving the film and sensitized paper, said frame being shown in open position; and

Fig. 5 is a diagrammatic view of the electrical circuits associated with my improved printing machine.

Referring more particularly to the drawing, wherein similar characters of reference designate like and corresponding parts throughout the various views, 1 designates the main body of my improved printing machine, the same being in the form of a rectangular table. The table 1 is provided with supporting legs 2 strengthened by means of vertical and transverse braces 3 and 4. The legs 2 are strengthened at their juncture with the top 1 by means of end and side boards 5 and 6. A base board 7 connected to the rearward legs of the machine and strengthens the same at this point, said base board serving a further purpose which will hereinafter appear. A rack 8 is mounted at the rear of the body 1 for supporting different sized printing frames when not in use.

The printing mechanism of my invention comprises a lamp housing 9 mounted beneath an opening 10 formed in the body 1, said housing having a bottom 11 upon which are arranged a plurality of sets of light sources 12 and 13 alternately operable and of different shades for a purpose which will hereinafter appear. The light sources 12 and 13 are intermittently and alternately controlled by means of a suitable switch mechanism the preferred form of which is hereinafter described in detail.

The film holding means of my invention preferably comprises a removable frame 14 provided with a tongue 15 receivable in a suitable recess 16 formed in the top 1, said frame 14 being secured in position by means of a sliding spring pressed bolt or locking member 17 best shown in Fig. 2. The member 17 is provided with a downwardly extending finger engaging portion 17'. The frame 14 is provided with a rectangular recess 18 and a shoulder 19 on which is mounted a transparent plate 20 on which is deposited the film and paper holding frame best shown in Fig. 4, designated 21 in its entirety. Referring specifically to Fig. 4 the frame 21 comprises a base portion formed with a pair of shoulders 22 and 23. The film is placed on the shoulder 23, and a retaining frame 24 hinged at 25 on the base frame 21 is adapted to be swung down onto the shoulder 22, said frame 24 having an internal inwardly bent flange for engagement with the film, securely gripping the same adjacent the shoulder 23. The frame 21 is placed within the frame 14 with the

supplemental frame uppermost and with the film lowermost so as to reproduce the image contained thereon on the sensitized paper, the latter being placed above the 5 frame 24. An ordinary wing nut or latch 27 carried by the frame 14 serves to retain the frame 21 within said frame 14, also maintaining the supplemental frame 24 in closed position.

10 I provide means for maintaining the film and sensitized papers in snug engagement with the transparent plate 20, said means comprising a pad holder 28 hinged at 29 to a block 30 mounted on the top 1. I provide 15 vide a pad 31 carried by the pad holder 28, said pad holder comprising a block 32 having screws 33 extending from the rearward face thereof. The block 32 is covered with felt or some similar soft material. The block 32 is engageable with the pad carrying member 28 by means of an elongated aperture 34 formed in said pad carrying member and having enlarged portions 35 and 36 to receive the screw heads 33, slight longitudinal movement of the pad engaging the screw head with the narrow portions of the flap 34 and firmly connect the pad to the holder. It will be readily apparent that various sized pads may be applied to the 20 pad holder, depending upon the sizes of printing frame employed.

The pad holder 28 is normally maintained in the position shown in Fig. 1 by means of a coil spring 37 connected at the point 38 to the pad holder and to the block. I provide 35 means for depressing the pad holder into engagement as a film retaining device, said means comprising an arm 39 hinged at 40 to a housing 41 carried by the rearward 40 margin of the top 1. A coil spring 42 connected with the housing and with said arm 39 normally maintaining the arm in the position shown in Fig. 1. An anti-friction roller 43 carried by the free end of the arm 45 engages the rear face of the pad holder 28 permitting relative movement between said pad holder and said arm. I provide means for moving the arm 39 to actuate the pad holder, said means including a connecting 50 rod 44 having a flattened portion 45 pivoted at 46 to an enlargement 47 formed on said arm 39. A foot pedal 48 hingedly mounted at 49 to the base board 7 is engaged with the connecting rod 44 by means of a wing nut 50 55 carried by the lower end of said rod. A coil spring 51 having its free ends fastened at 52 to a vertical panel 53 and to said foot pedal 48 serves to retain the foot pedal to uppermost position under a depression.

60 It will be readily apparent that during a printing operation it is essential that a strong well distributed light be used and that while placing the film and sensitized paper in position to be printed sufficient 65 light must be had to enable the operator to

clearly see what he is doing. Therefore, two light sources are provided in my improved printing machine, said light sources being intermittently and alternately supplied with electric current by means of a switch mechanism operated upon a depression and a return, respectively, of the pad holder 28. This switch mechanism is mounted on the rear wall 54 of the housing 41, said rear wall being secured in position by means of screws 70 55 or the like. The switch mechanism comprises two circuit closing members semi-diagrammatically illustrated in Fig. 5, and comprise base portions 56 and 57 mounted on the rear wall 54 in any suitable manner. Referring to the circuit closing member 56 I provide a terminal 58 extending outwardly from the base 56 and having an inwardly turned portion 59 normally engaged by a spring arm 60 forming the other terminal of 80 85 the switch which controls the red light circuit A in which is interposed a red color incandescent lamp heretofore designated 13.

The light for printing purposes comprises a plurality of white incandescent lamps 90 heretofore designated 12, said lamps being controllable by the switch 57 and arranged in sets, said switch having a terminal 61 engageable at times by a spring arm 62 forming the other terminal of the white light 95 circuits. Manually controllable switches S and S' are interposed in the white light circuits, for cutting either or both out when the film requires more light on one side than on the other.

100 I provide actuating means for the spring arms 60 and 62, said means including a pair of reciprocally mounted pins 63 and 64 provided with insulated tips 65 for normal engagement with said spring arms. The opposite ends of the pins normally project through the block 30 beyond the free marginal edge thereof to be engaged when the pad holder 28 is in the position shown in Fig. 2 by metallic wear plates 66 carried by 110 said pad holder.

115 In operation, the sensitized paper and film are placed in the frame 21 in the manner hereinbefore set forth, said frame being placed in position on the frame 14, said frame 14 having been previously placed in position in the opening 10. The proper sized pad is now placed on the pad holder and the foot pedal 48 depressed this movement brings the pad holder into a horizontal plane at the same time bringing the pad into engagement with the film and sensitized paper. At this time the pins 63 and 64 are moved rearwardly opening the switch 56 and closing the switch 57. This movement 120 lights the white light 12 and cuts out the red light 13. After the sensitized paper has been exposed the proper length of time the foot pedal is released, this automatically permitting the switch 56 to close and open 130

the switch 57. The lights now return to their former condition, namely, the red lamp lighting, and the white light being extinguished. It will be readily apparent that 5 various sized photographs may be printed in my improved printing machine, by virtue of the provision of the removable frame 14 which may be supplemented by the proper sized frame as desired.

10 From the above description taken in connection with the accompanying drawings, it is thought that a clear and comprehensive understanding of the construction, operation and advantages of my invention 15 may be had, and while I have shown and described my invention as embodying a specific structure, I desire that it be understood that I may make such changes on said structure as do not depart from the spirit 20 and scope of the invention as claimed.

What I claim as new and desire to secure by Letters Patent is:—

1. In a photographic printing machine of the class described, a base member, printing frames detachably associated with said base, and with each other, one of said frames receiving photographic sensitized paper and a film, a plurality of light sources adjacent thereto, means for retaining the 25 film and sensitized paper in position to be printed and means for alternately controlling said light sources.

2. In a photographic printing machine of the class described, a base member, printing 30 frames associated with said base member, one of said frames being adapted to receive a film and a piece of sensitized paper, means for retaining said film and sensitized paper in position to be printed, a plurality 35 of light sources, one of said light sources serving to print a picture on the sensitized

paper, the other light source being subdued and for the use of the operator, and circuit closing means associated with said film retaining means for automatically energizing 45 alternately said light sources.

3. In a photographic printing machine of the class described, the combination of a base and supporting legs therefor, of a lamp casing carried by said base, a main printing 50 frame carried by said base over said lamp casing, detachably associated frames carried by said main frame for holding a film and a piece of sensitized paper, a plurality of light sources in said lamp casing alternately operable, means for retaining said film and paper in position, said means comprising a hingedly mounted member and a pad carried thereby, means for depressing 55 said member into operative position, and 60 means operable by said member for alternately operating said light sources.

4. In a photographic printing machine of the class described, a base, a lamp casing associated with said base, a main frame 65 mounted above said lamp casing, a detachable supplemental frame associated with said main frame for containing a film and sensitized paper to be printed thereby, means for retaining said film and paper in 70 position, said means comprising a hingedly mounted member and a pad detachably carried thereby, actuating means for said member, a plurality of light sources in said lamp casing, and a plurality of switch elements actuatable by said member to open and close circuits for said light sources 75 whereby to alternately energize the same.

In testimony whereof I affix my signature hereto.

JAMES A. CHADDERTON.
